CLAIM

I claim the ornamental design for a measuring cup, as shown and described.

DESCRIPTION

FIG. 1 is a perspective view of the measuring cup.

FIG. 2 is a left side elevation view.

FIG. 3 is a top plan view.

FIG. 4 is a front elevation view.

FIG. 5 is a bottom plan view.

FIG. 6 is a right side elevation view.

FIG. 7 is a rear side elevation view.

FIG. 8 is a sectional view to show the interior along lines 8-8 of FIG. 3.

FIG. 9 is a perspective view of an alternative embodiment.

FIG. 10 is a left side elevation view of the alternative embodiment.

FIG. 11 is a top plan view of the alternative embodiment.

FIG. 12 is a front elevation view of the alternative embodiment.

FIG. 13 is a top plan view of the alternative embodiment.

FIG. 14 is right side elevation view of the alternative embodiment.

FIG. 15 is a rear elevation view of the alternative embodiment; and,

FIG. 16 is a cross sectional view along lines 16-16 of FIG. 13 of the alternative embodiment.
